CLAIM

The ornamental design for a photography lightbox, as shown and described.

DESCRIPTION

FIG. 1 is a view of the right side of the first embodiment of the photography lightbox.

FIG. 2 is a view of the left side of the first embodiment of the photography lightbox.

FIG. 3 is a view of the back side of the first embodiment of the photography lightbox.

FIG. 4 is a view of the front side of the first embodiment of the photography lightbox.

FIG. 5 is a view of the top side of the first embodiment of the photography lightbox.

FIG. 6 is a view of the bottom side of the first embodiment of the photography lightbox;

FIG. 7 is a perspective view at an angle of the top of the right side of the first embodiment of the photography lightbox.

FIG. 8 is a perspective view at an angle of the front of the bottom side of the first embodiment of the photography lightbox.

FIG. 9 is a perspective view at an angle of the back of the right side of the first embodiment of the photography lightbox.

FIG. 10 is a view of the right side of the second embodiment of the photography lightbox.

FIG. 11 is a view of the left side of the second embodiment of the photography lightbox.

FIG. 12 is a view of the back side of the second embodiment of the photography lightbox.

FIG. 13 is a view of the front side of the second embodiment of the photography lightbox.

FIG. 14 is a view of the top side of the second embodiment of the photography lightbox.

FIG. 15 is a view of the bottom side of the second embodiment of the photography lightbox.

FIG. 16 is a perspective view at an angle of the top of the right side of the second embodiment of the photography lightbox.

FIG. 17 is a perspective view at an angle of the front of the bottom side of the second embodiment of the photography lightbox.

FIG. 18 is a perspective view at an angle of the back of the right side of the second embodiment of the photography lightbox.

FIG. 19 is a view of the right side of the third embodiment of the photography lightbox.

FIG. 20 is a view of the left side of the third embodiment of the photography lightbox.
FIG. 21 is a view of the back side of the third embodiment of the photography lightbox.
FIG. 22 is a view of the front side of the third embodiment of the photography lightbox.
FIG. 23 is a view of the top side of the third embodiment of the photography lightbox.
FIG. 24 is a view of the bottom side of the third embodiment of the photography lightbox.
FIG. 25 is a perspective view at an angle of the top of the right side of the third embodiment of the photography lightbox.
FIG. 26 is a perspective view at an angle of the front of the bottom side of the third embodiment of the photography lightbox.
FIG. 27 is a perspective view at an angle of the back of the right side of the third embodiment of the photography lightbox.
FIG. 28 is a view of the right side of the fourth embodiment of the photography lightbox.
FIG. 29 is a view of the left side of the fourth embodiment of the photography lightbox.
FIG. 30 is a view of the back side of the fourth embodiment of the photography lightbox.
FIG. 31 is a view of the front side of the fourth embodiment of the photography lightbox.
FIG. 32 is a view of the top side of the fourth embodiment of the photography lightbox.
FIG. 33 is a view of the bottom side of the fourth embodiment of the photography lightbox.
FIG. 34 is a perspective view at an angle of the top of the right side of the fourth embodiment of the photography lightbox.
FIG. 35 is a perspective view at an angle of the front of the bottom side of the fourth embodiment of the photography lightbox.

FIG. 36 is a perspective view at an angle of the back of the right side of the fourth embodiment of the photography lightbox.
FIG. 37 is a view of the right side of the fifth embodiment of the photography lightbox.
FIG. 38 is a view of the left side of the fifth embodiment of the photography lightbox.
FIG. 39 is a view of the back side of the fifth embodiment of the photography lightbox.
FIG. 40 is a view of the front side of the fifth embodiment of the photography lightbox.
FIG. 41 is a view of the top side of the fifth embodiment of the photography lightbox.
FIG. 42 is a view of the bottom side of the fifth embodiment of the photography lightbox.
FIG. 43 is a perspective view at an angle at an angle of the top of the right side of the fifth embodiment of the photography lightbox.
FIG. 44 is a perspective view at an angle of the front of the bottom side of the fifth embodiment of the photography lightbox; and,
FIG. 45 is a perspective view at an angle of the back of the right side of the fifth embodiment of the photography lightbox.
A photography lightbox is a fabric reflector that attaches to studio lighting via a connector to create soft lighting by diffusing the strobe flash.
The portions of the photography lightbox drawn in phantom (using dashed lines) are not part of the design being claimed, and only indicate the environment of the claimed design of the photography lightbox.
